COMPOSITE GARMENT

Joseph Siegel, New York, N. Y.

Application April 10, 1936, Serial No. 73,608

14 Claims. (Cl. 2-97)

My present invention relates to improvements in garments and more particularly to the provision of a pair of garments which may be worn singly or may be removably secured together to provide a third garment.

It has heretofore been proposed to provide removable linings for men's overcoats, these linings being detachably connected to the coat in cold weather and being readily removable to provide a light weight top coat in warmer weather. The linings when removable serve no useful purpose. Such linings, furthermore, have been for the most part of the sleeveless type which served to keep the body of the wearer warm without providing adequate protection for the arms.

In accordance with one feature of the present invention I propose to provide a detachable lining of this type which may be conveniently attached to the inside of an overcoat and which, upon removal from the coat, is capable of serving as a separate wearable garment of substantially conventional appearance. In a preferred embodiment of the invention the lining when removed serves as a bathrobe or lounging robe.

Another feature of the invention is the provision of a separate garment member suitable for use as a lining and so cooperating with the overcoat that the securing means between the lining and the coat are entirely concealed when the lining has been removed from the coat and is in use as a robe, the securing means are again completely concealed.

Inasmuch as I prefer to utilize a line of metallic teeth on the lining and a line of metallic teeth on the coat and to secure the lining to the coat by a conventional slide fastener for such interengaging lines of teeth it is important that the body of the wearer of the bathrobe should be protected from the teeth when the convertible bathrobe and lining is worn as a robe.

My present invention involves a construction in which the teeth are not only concealed from view when the device is used either as a bathrobe or as a coat lining but in which suitable means is provided for automatically covering the teeth when the convertible garment is used as a robe and preventing any contact thereof with the body of the wearer.

When my improved convertible garment is employed as a lining for a coat the appearance of the coat is entirely conventional and in addition to lining the body portion of the coat the sleeves of the robe line the sleeves of the coat and provide the necessary warmth for the arms. When

this conventional lining element is removed an entirely conventional light weight overcoat is left and the erstwhile lining affords a bathrobe of entirely conventional appearance.

While I have referred to the provision of an element which may be used as a coat lining or a bathrobe is to be understood that it is within the scope of the invention to provide an overcoat lining which could be converted into various other types of garments, such for instance, as 10 smoking jackets, raincoats, etc.

Many of the advantages of the invention will become more fully apparent from the following detailed description taken in connection with the accompanying drawings wherein:

Fig. 1 is a perspective view of an overcoat with my improved lining in place, the coat being open to expose the lining and parts of the coat being broken away for the sake of clearness. This view also illustrates the manner in which the lining 20 may be removed from the coat.

Fig. 2 is a considerably enlarged transverse sectional view on the line 2-2 of Fig. 1.

Fig. 3 is a similar view with the lining detached.

Fig. 4 is a view taken on the line 3-3 of Fig. 1.

Fig. 5 is a view similar to Fig. 4 but showing the lining detached.

Fig. 6 is a sectional detail through the cuff portion of the coat with the lining in place. This view being taken approximately on the line 6-6 of Fig. 13.

Fig. 7 is a perspective view showing the inside of the bathrobe when the latter has been removed, certain portions of the robe being broken away and other portions being folded back to more clearly disclose the construction.

Fig. 8 is an enlarged transverse sectional detail on the lines 8-8 of Fig. 7.

Fig. 9 is a view similar to Fig. 8 but showing the covering flap for the metal teeth folded back to expose them for engagement with the teeth carried by the coat.

Fig. 10 is a sectional detail on the line 10-10 of Fig. 7.

Fig. 11 is a view similar to Fig. 10 but showing the shawl collar of the bathrobe rolled back.

Fig. 12 is an enlarged perspective detail of the lapel portion of the coat.

Fig. 13 is a perspective view showing the overcoat in position upon the wearer.

Fig. 14 is a similar view showing the bathrobe in use.

Fig. 15 is an enlarged detail through the bathrobe cuff taken on the line 15-15 of Fig. 14.

Fig. 16 is a perspective view illustrating the collar portion of a slightly modified bathrobe and interlining.

Fig. 17 is a sectional view on the line 17-17 of Fig. 16.

Fig. 18 is a view similar to Fig. 17 showing the manner in which the "Zipper" is concealed when the interlining is used as a bathrobe.

Fig. 19 is a view similar to Fig. 17 but illustrating the relationship of the bathrobe collar portion to an overcoat when the interlining is in place in the coat.

Referring with more particularity to the drawings I have used the reference numeral 20 to indicate the body of an overcoat. This coat may be of entirely conventional external appearance and of substantially conventional appearance when viewed from the inside. I prefer that the inside facings 21 be of slightly less width than 20 usual in order to assist in providing room for the accommodation of an interlining 22 of substantial width.

The facing 21 cooperates with the body of the overcoat to provide a concealed inwardly facing 25 pocket or channel 23 which extends from one lower corner of the coat around the collar portion thereof and down to the other corner of the coat. Secured and concealed within this pocket or channel 23 is a strip of flexible material 24 carrying one set of metallic teeth 25 of the "Zipper" type. The teeth 25 are adapted to cooperate with corresponding teeth 26 carried by a strip 27 which is sewed to the body portion 22 of the interlining. A slide fastener element 35 30 permanently attached to the interlining is operable to effect interengagement of the two teeth sets 25 and 26 throughout the full length of the channel or pocket 23 and the intermeshed teeth will be protected and concealed by the 40 inwardly extending flap of the facing so that the interlining will present a substantially conventional appearance when in position within the coat.

The strip 27 is not sewed to the extreme edge 45 of the interlining but the interlining is folded back to provide a flap 29 and the strip 27 is sewed to the interlining closely adjacent the fold where this flap turns back. A strip of material 30 slightly wider than the "Zipper" strip 27 is secured to the flap 29 along a line somewhat inwardly of the fold line of the flap.

Figs. 2, 8, and 9 illustrate the manner in which the flap 29 and strip 30 function when the lining is in place and when the lining has been removed. It will be observed in Figs. 2 and 8 that when the interlining is in place in the coat the flap 29 lies between the body 22 of the interlining and the coat and the strip 30 extends into the channel 23 lying between the interlocked "Zipper" teeth and the body of the coat. When the lining is removed from the coat, however, the flap 29 folds over in the manner illustrated in Fig. 9 to afford an extension of the coat body and the strip 30 turning inwardly completely conceals the "Zipper" teeth 26 as well as the strip 27 which carries them. Thus when the lining is removed and worn as a robe the strip 30 intervenes between the strip 27 and the body of the wearer, not only concealing the teeth of the seam 70 but preventing any contact thereof of the body of the wearer.

It will be observed that if a narrow facing is used the additional width provided by the flaps 29 will permit the robe when fully opened to completely encircle the body of the wearer and pro-

vide overlapping edges which may be secured together by one or more separable fastening devices, such for instance, as a button 31 carried by one of the flaps 29 and cooperating with a corresponding buttonhole in the opposite flap. 5

It is desirable not only to provide a collar 32 for the coat but to arrange this collar in such a fashion that the "Zipper" teeth in the region of the collar cannot contact the body of the wearer when the robe is worn. Where a shawl 10 collar such as that illustrated in Fig. 14 for instance is desired a problem is presented due to the fact that the collar must be so attached to the body of the coat as to fold in one direction whereas the flap 29 must be so attached as to 15 fold in the opposite direction when the robe is worn and at the same time the line of "Zipper" teeth must be uninterrupted.

I have solved this problem by the provision of a split lapel structure, the upper portion of the 20 lapel being formed by the collar proper and the lower portion 33 by the turned back upper edges of the flaps 29. The collar is unattached to the body of the coat near its extreme lower ends to afford tabs or flaps 32a which will overlap the 25 lapel-forming portions 33 of the flaps 29. Above the point where the flaps 29 terminate the collar 32 is sewn to the inside of the interlining 22 by a line of stitching 34, which line of stitching 30 may, if desired, assist in securing the "Zipper" strip 27 in place.

When the interlining is in place within the coat the collar 32 lies against the inner face of the interlining so as not to interfere with the application of the "Zipper" strip. This collar may be held down flatly by the provision of snap fasteners or equivalent devices 35 carried by the collar and by the body of the interlining respectively. When the interlining is removed and used as a robe and the collar 32 folds over the 40 edge of the "Zipper" strip from the position of Fig. 10 to the position of Fig. 11, the collar itself serving to conceal the "Zipper" strip and the latter strip serving, if desired, as a stand for the collar. As the collar is swung from this position of Fig. 10 to the position of Fig. 11 flaps 32a 45 will overlap to some extent the lapel forming portions 33 of the flaps 29 and give the split lapel effect illustrated in Fig. 14.

One objection to the use of removable overcoat interlinings has been their failure to provide adequate protection against cold for the arms of the wearer. By my present invention this is overcome since the robe forming interlining is provided with sleeves 36 which lie within the sleeve 37 of the overcoat. Preferably the sleeves of the robe are formed with turned back cuffs 38 which serve to conceal snap fastener elements 39 when the robe is removed from the coat. When the robe is used as an interlining, however, the cuffs 38 may be turned down to permit engagement of the fastener elements 39 with corresponding elements 40 secured within the overcoat sleeves in the region of the cuffs of the latter. Fig. 6 shows the robe sleeve 65 snapped in position in the coat sleeve and Fig. 15 shows the cuff of the robe sleeve when the robe has been removed from the coat. The possibility of the robe sleeve becoming displaced from the coat sleeve during normal use of the 70 overcoat is quite remote but I prefer to use some means of attachment between the two sleeves to avoid any possible danger of the interlining sleeves slipping out of position when removing the overcoat from a velvet jacket or other un- 75

usual type material which creates a great deal of friction between itself and the interlining sleeve.

In Figs. 16 to 19 inclusive I have illustrated 5 another type of collar for the robe. Here the collar employed is not of the shawl type but is in the form of comparatively narrow strip of collar forming material which affords a stand-up collar. This collar is formed of two separate 10 strips 40 and 41 secured by a line of stitching 42 to the edge of the body portion 22 of the robe. The strip 40 is slightly wider than the strip 41 and is provided with an inwardly turned flap 43 which lies between the strips 40 and 41. The 15 "Zipper" strip 27 in this case is sewed to the free edge of the collar forming strip 41 and the edge of the collar forming strip 40 with its inwardly turned flap extends outwardly beyond the "Zipper" and is adapted to lie in the groove or 20 channel 23.

Fig. 17 shows the position of the collar member when the robe is to be applied as an interlining for an overcoat and Fig. 19 shows this interlining in applied position. Obviously when 25 the robe is removed from the coat the teeth of the strip 27 would directly contact the neck of the wearer but to prevent this the flap 43 is pulled outwardly and dropped into position between the strip 27 and the neck of the wearer. 30 This is illustrated in Fig. 18 with the strip 41 lying between the strip 40 and its attached flap 43. In order to secure the strips in this position cooperating snap fastener elements 44 may be employed on the inner side of the strip 27 and 35 the inner face of the flap 43.

In order to simplify the illustration of the invention I have omitted certain conventional details such for instance as the showing of the silk facing in the shoulder portion of the interlining 40 and the showing of conventional collar stands, piping, etc., in the coat and the robe. Suffice it to say that with the interlining removed the coat presents the standard appearance of a light weight overcoat. The robe itself is completely 45 tailored inside and out so that when it is used as an interlining the standard appearance of the overcoat is preserved and when it is used as a robe the standard appearance of the robe is preserved. Such additional features as pockets in 50 the robe, etc., may, of course, be provided if desired.

The entire construction is so designed that with the interlining in position the coat will not be bulky or bulgy. The flat metal seam contributes 55 materially to this result and the turned back flaps 29 only occupy a space which would normally be occupied by extending the facings of the overcoat further inwardly so that there is substantially no increased bulk at that point.

60 As above suggested I have illustrated and described the interlining as suitable for use as a bathrobe or lounging robe. It is within the spirit of the invention to provide any two coat like garments capable of individual use and so designed they will also be capable of assembly with one garment serving as an interlining for the other.

I claim,

1. A composite garment of the class described 70 including an overcoat having a facing on the inside thereof following the edges of the coat, said facing cooperating with the body of the coat to provide an inwardly opening channel, a strip of flexible material concealed within the channel and having a plurality of teeth adapted to de-

fine part of a metallic seam, a second coat-like garment adapted to serve as a removable interlining for the coat, said garment having a tooth carrying strip sewed thereto inwardly of the edges of the garment, that portion of the second garment between the last mentioned strip and the garment edge constituting a flap of width greater than the depth of the channel to be folded inwardly between the body of the coat proper and the body of the interlining garment when the two sets of teeth are interlocked. 10

2. A composite garment of the class described including an overcoat having a facing on the inside thereof following the edges of the coat, said facing cooperating with the body of the coat to provide a continuous inwardly opening channel, a strip of flexible material concealed within the channel and having a plurality of teeth adapted to define part of a metallic seam, a second coat-like garment adapted to serve as a removable interlining for the coat, said interlining garment having a tooth carrying strip sewed thereto inwardly of the edges thereof, that portion of the interlining garment between the last mentioned strip and the garment edge constituting a flap of width greater than the depth of the channel to be folded inwardly between the body of the coat proper and the body of the interlining garment when the two sets of teeth are interlocked, said flap portion carrying a second strip of material 20 adapted to lie in the channel of the overcoat when the garment is used as an interlining and adapted to conceal the tooth carrying strip of the garment when said interlining garment is removed from the coat. 30

3. A composite garment of the class described including an overcoat having on the inside thereof following the edges of the coat, a continuous inwardly opening channel, a strip of flexible material concealed within the channel and having a plurality of teeth adapted to define part of a metallic seam, a bathrobe adapted to serve as a removable interlining for the coat, said bathrobe having a tooth carrying strip sewed thereto inwardly of the edges thereof, that portion of the bathrobe between the last mentioned strip and the bathrobe edge constituting a flap of width greater than the depth of the channel to be folded inwardly between the body of the coat proper and the body of the bathrobe when the two sets 40 of teeth are interlocked. 45

4. A composite garment of the class described including an overcoat having on the inside thereof following the edges of the coat, a continuous inwardly opening channel, a strip of flexible material concealed within the channel and having a plurality of teeth adapted to define part of a metallic seam, a bathrobe adapted to serve as a removable interlining for the coat, said bathrobe having a tooth carrying strip sewed thereto inwardly of the edges thereof, that portion of the bathrobe between the last mentioned strip and the bathrobe edge constituting a flap to be folded inwardly between the body of the coat proper and the body of the bathrobe when the two sets of teeth are interlocked, and means 55 operative to conceal the tooth carrying strip of the bathrobe when said robe is removed from the coat. 60

5. A composite garment of the class described 70 including an overcoat having on the inside thereof following the edges of the coat, a continuous inwardly opening channel, a strip of flexible material concealed within the channel and having a plurality of teeth adapted to define part 75

of a metallic seam, a bathrobe adapted to serve as a removable interlining for the coat, said bathrobe having a tooth carrying strip sewed thereto inwardly of the edges thereof, that portion of 5 the bathrobe between the strip and the bathrobe edge constituting a flap to be folded inwardly between the body of the coat proper and the body of the bathrobe when the two sets of teeth are interlocked, and means operative to conceal the 10 tooth carrying strip of the bathrobe when said robe is removed from the coat, comprising a strip of material sewed to the flap adapted to lie in the channel when the robe is used as an interlining and to cooperate with the body of the robe 15 to afford a concealing channel for the tooth carrying strip of the robe when the latter is removed from the coat.

6. A composite garment of the class described including an overcoat having a facing on the inside thereof following the edges of the coat, said facing cooperating with the body of the coat to provide a continuous inwardly opening channel, a second coat-like garment adapted to serve as a removable interlining for the coat, said interlining garment and said coat having complementary detachable securing devices concealed by said channel, that portion of the interlining garment between the strip and the interlining garment edge constituting a flap of width greater 30 than the depth of the channel to be folded inwardly between the body of the coat proper and the body of the garment when the securing devices are connected together.

7. A composite garment of the class described including an overcoat having a facing on the inside thereof following the edges of the coat, said facing cooperating with the body of the coat to provide a continuous inwardly opening channel, a second coat-like garment adapted to serve as 35 a removable interlining for the coat, said interlining garment and said coat having complementary detachable securing devices concealed by said channel, that portion of the interlining garment between the strip and the interlining garment edge constituting a flap to be folded inwardly between the body of the coat proper and the body of the interlining garment when the securing devices are connected together, a collar for the interlining garment shiftable to expose certain of 45 the securing devices for engagement with those of the coat when the garment is used as an interlining or to conceal them when the interlining garment is removed from the coat.

8. A composite garment of the class described including an overcoat having a facing on the inside thereof following the edges of the coat, said facing cooperating with the body of the coat to provide a continuous inwardly opening channel, a strip of flexible material concealed within the 50 channel and having a plurality of teeth adapted to define part of a metallic seam, a second coat-like garment adapted to serve as a removable interlining for the coat, said interlining garment having a tooth carrying strip sewed thereto inwardly of the edges thereof, that portion of the interlining garment between the strip and the interlining garment edge constituting a flap to be folded inwardly between the body of the coat proper and the body of the interlining garment 55 when the two sets of teeth are interlocked, said flaps carrying cooperating securing devices for coaction when the interlining garment is removed from the coat.

9. A composite garment of the class described including an overcoat having a narrow facing on 60

the inside thereof following the edges of the coat, said facing cooperating with the body of the coat to provide a continuous inwardly opening channel, a strip of flexible material concealed within the channel and having a plurality of teeth 5 adapted to define part of a metallic seam, a second robe-like garment adapted to serve as a removable interlining for the coat, said interlining garment having a tooth carrying strip sewed thereto for coaction with the tooth carrying strip of the coat, and a flap carried by the interlining garment adapted to lie in the channel of the overcoat when the garment is used as an interlining and adapted to conceal the tooth carrying strip of the interlining garment when the latter 10 is removed from the coat.

10. A composite garment of the class described including an overcoat having at the inside thereof closely following the edges of the coat, a continuous inwardly opening channel, a strip of flexible material concealed within the and extending the full length of the channel and having a plurality of teeth adapted to define part of a metallic seam, a second garment adapted to serve as a removable interlining for the coat and including a collar portion, said interlining garment having a tooth carrying strip sewed thereto inwardly of the edges thereof, the portions of the interlining garment between the strip and the garment edge constituting flaps to be folded inwardly between 20 the body of the coat proper and the body of the garment when the two sets of teeth are interlocked and adapted to be connected together to close the interlining garment when the latter is worn separately.

11. A composite garment of the class described including an overcoat having at the inside thereof closely following the edges of the coat, a continuous inwardly opening channel, a strip of flexible material concealed within and extending the 25 full length of the channel and having a plurality of teeth adapted to define part of a metallic seam, a second garment adapted to serve as a removable interlining for the coat and including a collar portion, said interlining garment having a tooth carrying strip sewed thereto inwardly of the edges thereof, the portions of the interlining garment between the strip and the garment edge constituting flaps to be folded inwardly between the body of the coat proper and the body of the 30 garment when the two sets of teeth are interlocked and adapted to be connected together to close the interlining garment when the latter is worn separately, said collar portion being 35 folded down against the inside of interlining when the latter is in place in the coat and being foldable over the tooth carrying strip of the interlining to conceal the teeth when the interlining is worn as a separate garment.

12. A composite garment of the class described including an overcoat having at the inside thereof closely following the edges of the coat, a continuous inwardly opening channel, a strip of flexible material concealed within and extending the 40 full length of the channel and having a plurality of teeth adapted to define part of a metallic seam, a second garment adapted to serve as a removable interlining for the coat and including a collar portion, said interlining garment having a tooth carrying strip sewed thereto inwardly of the 45 edges thereof, those portions of the interlining garment between the strip and the interlining garment edge constituting flaps to be folded inwardly between the body of the coat proper and the body of the interlining garment when the two 50

- sets of teeth are interlocked and adapted to be connected together to close the interlining garment when the latter is worn separately, said collar portion extending beyond the tooth carrying strip and lying partly in the channel when the interlining is in place and including a foldable flap to conceal and prevent bodily contact with the teeth of the interlining garment when the latter is worn alone.
- 10 13. A composite garment of the class described including an overcoat having at the inside thereof closely following the edges of the coat, a continuous inwardly opening channel, a strip of flexible material concealed within and extending 15 the full length of the channel and having a plurality of teeth adapted to define part of a metallic seam, a second garment adapted to serve as a removable interlining for the coat and including a collar portion, said interlining garment 20 having a tooth carrying strip sewed thereto inwardly of the edges thereof, those portions of the interlining garment between the strip and the interlining garment edge constituting flaps to be folded inwardly between the body of the 25 coat proper and the body of the interlining garment when the two sets of teeth are interlocked and adapted to be connected together to close the interlining garment when the latter is worn separately, said collar portion being 30 folded down against the inside of interlining when the latter is in place in the coat and being foldable over the tooth carrying strip of the interlining to conceal the teeth when the interlining is worn as a separate interlining garment, said flap portions carrying strips of material adapted to lie in the channel of the overcoat when the interlining garment is used as 35 an interlining and adapted to lie between the tooth carrying strip of the garment and the body of the wearer when said interlining garment is removed from the coat and worn alone.
14. A composite garment of the class described including an overcoat having at the inside thereof closely following the edges of the coat, a continuous inwardly opening channel, a strip of flexible material concealed within and extending 10 the full length of the channel and having a plurality of teeth adapted to define part of a metallic seam, a second garment adapted to serve as a removable interlining for the coat and including a collar portion, said interlining garment having a tooth carrying strip sewed thereto inwardly of the edges thereof, those portions of the interlining garment between the strip and the interlining garment edge constituting flaps to be folded inwardly between the body of the coat proper and the body of the interlining garment when the two sets of teeth are interlocked and adapted to be connected together to close the interlining garment when the latter is worn separately, said collar portion extending 15 beyond the tooth carrying strip and lying partly in the channel when the interlining is in place and including a foldable flap to conceal and prevent bodily contact with the teeth of the interlining garment when the latter is worn alone, said flap portions carrying strips of material 20 adapted to lie in the channel of the overcoat when the interlining garment is used as an interlining and adapted to lie between the tooth carrying strip of the interlining garment and the body of the wearer when said interlining garment is removed from the coat and worn alone.

JOSEPH SIEGEL.
